[57] CLAIM

The ornamental design for an electrical cable connector boot, as shown and described.

DESCRIPTION

FIG. 1 is a perspective view of the electrical cable connector boot according to the present invention;

FIG. 2 is a perspective view of the electrical cable connector boot shown in FIG. 1;

FIG. 3 is a top view of the electrical cable connector boot shown in FIG. 1;

FIG. 4 is a front view of the electrical cable connector boot shown in FIG. 1;

FIG. 5 is a bottom view of the electrical cable connector boot shown in FIG. 1;

FIG. 6 is a left side view of the electrical cable connector boot shown in FIG. 1;

FIG. 7 is a right side view of the electrical cable connector boot shown in FIG. 1;

FIG. 8 is a rear view of the electrical cable connector boot shown in FIG. 1;

FIG. 9 is a perspective view of a second embodiment of the electrical cable connector boot according to the present invention;

FIG. 10 is a perspective view of the embodiment of FIG. 9;

FIG. 11 is a top view of the embodiment of FIG. 9;

FIG. 12 is a front view of the embodiment of FIG. 9;

FIG. 13 is a bottom view of the embodiment of FIG. 9;

FIG. 14 is a left side view of the embodiment of FIG. 9;

FIG. 15 is a right side view of the embodiment of FIG. 9;

and,

FIG. 16 is a rear view of the embodiment of FIG. 9.
